UNITED STATES PATENT OFFICE.

GEORGE G. GUY, OF BATAVIA, ILLINOIS, ASSIGNOR TO UNITED STATES WIND ENGINE & PUMP COMPANY, OF BATAVIA, ILLINOIS, A CORPORATION OF ILLINOIS.

TIE-ROD CONNECTION.

SPECIFICATION forming part of Letters Patent No. 752,065, dated February 16, 1904.

Application filed March 16, 1903. Serial No. 147,896. (No model.)

To all whom it may concern:

Be it known that I, GEORGE G. GUY, a citizen of the United States, residing at Batavia, in the county of Kane and State of Illinois, have invented certain new and useful Improvements in Tie-Rod Connections, of which the following is a specification.

My invention relates to tie-rod or brace-rod connections adapted for use in metallic structures—as, for example, for connecting tie or brace rods to the girders and columns of towers for wind-engines and the like.

The object of the invention is to provide an improved connection for use in such work as will allow the tie or brace rod the necessary amount of movement or play with respect to its associated column or girder; and the invention consists in the details of construction hereinafter described, and specifically pointed out in the claims.

In the accompanying drawings, Figure 1 is a side elevation of a section of a column or girder provided with my improved tie-rod connections. Fig. 2 is a sectional view on the line 2 2 of Fig. 1. Fig. 3 is a sectional view on the line 3 3 of Fig. 2. Fig. 4 is a detail bottom plan view of the form of shoe shown in the other figures, and Fig. 5 is a top plan detail view of the washer.

Referring to the drawings, the reference-letter A represents a section of any suitable girder or column—such, for example, as are employed in tower constructions—and which has a flat face or tread to which a suitable clip or bracket B is attached by any suitable means. The bracket or clip B may be of any desired form, but preferably is an angular plate of the general outline shown in the drawings and adapted to be attached to the tread of its associated column at its extremities by suitable bolts or rivets. By means of this construction the device is attached to the tread of the column in such position as to allow the attaching bolts or rivets to pass through the tread, which is the heaviest and strongest portion of the column, instead of through the weaker and lighter web. Moreover, this form of clip provides for the use of top and bottom

attaching bolts or rivets, whereby a plurality of such attaching means may be employed, and the strain is more directly in the line of the attaching devices. The bracket or clip is provided with an outwardly-flaring hole or passage b to loosely receive the threaded end of the tie-rod C. Within the bracket or clip is located a washer c, which may be a separate element or may be made integral with the clip. The washer is provided with an outwardly-flaring passage which registers with the passage b of the clip and loosely receives the end of the tie or brace rod. The washer is provided with a seat or depression around its passage substantially cup-shaped in cross-section and adapted to receive the rounded portion of a semispherical shoe c', which also is provided with a passage for the rod and which may or may not be interiorly threaded for engagement with the thread of the rod. The end of the rod makes threaded connection with a suitable threaded nut c'', against which the flat face of the shoe bears and which secures the parts together. It is obvious that the shoe and nut may be either separate elements or may be made integral.

When the parts are assembled as shown in the drawings, the brace or tie-rod is connected with the tread of the column or girder and may have such play within its seat as is necessary when assembling the parts of the tower or similar structure or when for any reason the connected girders or columns move in relation to each other.

In assembling the parts the clip or bracket is attached to the associated column. The threaded end of the tie-rod is then passed through the opening b and the washer, and the shoe and nut are suitably secured in place.

Having described my invention, I claim—

1. In a device of the class described, a tie-rod, a clip or bracket having a passage to freely receive said rod, a washer on the clip having a rounded seat, and a shoe having a complementary rounded face seated on the washer, and means to hold the shoe on the end of the rod.
2. In a device of the class described, a girder

or column having a tread, an angular clip or bracket secured to the tread and having a suitable passage, a tie-rod whose end passes freely through said passage, a washer within the 5 bracket and loosely surrounding the end of the rod, and a shoe on the end of the rod, the washer and shoe having coacting seating portions.

3. A tie-rod connection consisting of a rod having a threaded end, a clip or bracket having 10 a flaring passage, a washer loosely surrounding the end of the rod and having a cup-shaped seat, a shoe having a curved portion adapted to said seat, and a nut threaded upon the end of the rod.
- 15 4. In a device of the class described, a girder

or column, an angular clip secured at its ends to the girder and provided with an aperture, a washer on the clip having a coinciding aperture and a concave seat surrounding such aperture, a tie-rod passing freely through the 20 coinciding apertures, a shoe on the rod and having a convex face resting on the washer-seat, and a nut engaging the end of the rod and holding the shoe in place.

In testimony whereof I affix my signature in 25 presence of two witnesses.

GEORGE G. GUY.
